(Cl. D74—2)

To all whom it may concern:

Be it known that I, Nathan W. Roop, a citizen of the United States, residing at Columbus, in the county of Franklin and State of Ohio, have invented a new, original, and ornamental Design for a File Box or Similar Article, of which the following is a specification, reference being had to the accompanying drawing, forming a part thereof.

Fig. 1 is a perspective view looking toward a front corner of a file box or similar article showing my new design;

Fig. 2 is a perspective view looking toward a rear corner thereof;

Fig. 3 is a perspective view showing the lid of the box open; and

Fig. 4 is a bottom plan view.

I claim:

The ornamental design for a file box or similar article, substantially as shown.

NATHAN W. ROOP.
